AUTOMATIC NEEDLE BAR POSITIONER
Anthony A. Ciccotelli, Jr., 505 Goff Ave.,
Oaklyn, N.J. 08107
Filed Oct. 11, 1965, Ser. No. 494,655
5 Claims. (Cl. 112—221)

ABSTRACT OF THE DISCLOSURE

An automatic needle bar positioner on a sewing machine head having an aperture through the top with a needle drive bar reciprocating therethrough between upper and lower stroke limits comprising a sleeve affixed in said aperture between said head and said bar, said sleeve including an externally threaded portion extending above said top, a collar removably affixed on said bar over said sleeve, a biasing means bearing against said collar and urging said bar in a direction parallel to reciprocation thereof, to position said bar while said sewing machine is at rest, at a stroke limit of said reciprocating drive bar upon cessation of said reciprocation, and a hollow elongated tubular cap with an open internally threaded end engaging said threaded portion to enclose the upper end of said bar, collar and biasing means, said cap being readily unscrewed and said collar readily removed for an interchange of said biasing means to alternate positions between said collar and sleeve and said collar and cap, respectively, thereby providing a selective positioning of said bar to one of said stroke limits.

This invention relates in general to sewing machines, and in particular, to a device for stopping a reciprocating needle drive bar at a desired position.

The highly competitive garment industry employs skilled artisans to operate sewing machines at a high rate of production. Naturally, sewing machines with time saving features are very desirable. Contemporary high speed sewing machines have a disadvantage in that the needle is often out of position upon stoppage of the machine. That is, the needle is at a position other than the up or down stroke limit, requiring a manual positioning of the needle for removal of the work piece or a change in stitch direction. A great deal of time may be saved by my inexpensive invention which adapts existing sewing machines for an automatic positioning of the needle at an up or down stroke limit.

Therefore, to overcome the foregoing and other difficulties of the prior art, it is the general object of this invention to provide a device for existing sewing machines which automatically positions a needle upon stoppage of the machine.

It is an object of this invention to provide an automatic needle bar positioner which is adaptable to position a needle at an up or down stroke limit, as desired.

Another object of this invention is to provide an automatic needle bar positioner which is economic and simple in operation, requiring a minimum of maintenance.

A further object of this invention is to provide an automatic needle bar positioner which is economical to pro-

2

duce by utilizing conventional, currently available standard components that lend themselves to standard mass production manufacturing techniques.

Other objects and a fuller understanding of the invention may be had by referring to the following description and claims, taken in conjunction with the accompanying drawing, in which:

FIGURE 1 represents an end elevation of a sewing machine and automatic needle bar positioner in cross section;

FIGURE 2 is an exploded perspective view of an automatic needle bar positioner;

FIGURE 3 is a partial end elevational view similar to FIGURE 1 illustrating an alternate adaption of the invented device; and

15 FIGURE 4 is a perspective view showing a rotating shuttle hook, modified in accordance with the present invention.

Referring to the drawings in detail, wherein like numerals indicate like elements, there is shown in FIGURE 20 1 a drawing of a sewing machine indicated generally by the numeral 10. The machine 10 may be a standard industrial sewing machine having a hand wheel 12, a head 13 (in section), a needle drive bar 14, a needle 15, a pressure foot 16, and a rotary shuttle hook 18. A conventional drive to reciprocate the drive bar 14 through apertures at the top and bottom of head 13 is provided by a rotary shaft 19 which is connected to bar 14 through the standard crank linkages shown in FIGURE 1.

Normally, the apertures at the top and bottom of head 30 13, through which drive bar 14 extends and reciprocates are lined by bushings, such as that illustrated at 17. The invented device is utilized for adaption of existing machinery, therefore, a replacement sleeve 20 is included as a substitute for the bushing originally at the top of head 35 13. The sleeve 20 has an enlarged externally threaded end portion 22, which extends above the top of head 13 when the sleeve is inserted in place, as indicated. A set screw 21, provided for the original bushing, firmly affixes the sleeve 20 in place within the aperture in head 13.

40 A removable collar 25 fits on a portion of bar 14 extending above the sleeve 20. Set screw 27 may be tightened to affix the collar 25 at a desired position on bar 14. A biasing means is provided by the helical coil compression spring 30, which fits around the bar 14 with one end bearing 45 against collar 25.

The bar 14, sleeve 20, collar 25 and spring 30 are enclosed by a hollow elongated cap 35, as illustrated. Sufficient clearance is provided between the inside surfaces of the cap 35, the collar 20 and the upper stroke limit of bar 14, to enable unhindered reciprocation therein. The open end of cap 35 is internally threaded, as indicated, for engagement with the externally threaded portion 22 of sleeve 20. The opposite, enclosed end of cap 35 provides a bearing surface at 37 for the spring 30 in the alternate adaption of FIGURE 3. A slot 36 may be provided to facilitate the placement and removal of the cap 35 by means of a tool such as a screwdriver. It is understood, of course, that other well known means may be employed for a quick and convenient placement or removal of the cap 35. For example, a square or hexagonal shape together with an appropriate wrench, or knurled surfaces for

the fingers may be provided for unscrewing the cap 35. In some instances, the original drive bar of the sewing machine may not extend a sufficient distance above the threaded end 22 of sleeve 20 to accommodate the collar 25 and the spring 30. In such cases it will be necessary to provide an elongated replacement bar 14. For universal application, on all sizes of machines, it is proposed that the replacement for drive bar 14 have a hollow axial bore, internally threaded at one end 53 to receive threaded stud portions of bar extension sections (not shown). Thus, an appropriate replacement length may be accomplished by merely adding the proper size of replacement section. Otherwise, a machine screw 50 may be screwed into bore 53 to cap the replacement bar 14 as shown.

The operation of sewing machines utilizing the invented automatic needle bar positioner device may be controlled by a conventional sewing machine transmitter, which is operated by a foot pedal or the like. Sewing machine transmitters are well known in the art, serving to control motive power to the machine by alternate engagement between a clutch and a brake. Since the transmitter is conventional and forms no part of the present invention, no further description is necessary. However, for best operation of the invented device it is desirable that the transmitter be adjusted, in a manner familiar to those skilled in the use of sewing machines, to provide a neutral position; that is, with the clutch and brake both disengaged. For example, the transmitter adjustment may be such that pressure to the front of the foot pedal by the toe, or to the back of the pedal by the heel, will engage the clutch and brake, respectively, but removal of all pressure from the pedal will free the needle bar mechanism from engagement with either clutch or brake.

If it is desired to stop the machine with the needle at an upper stroke limit, the invented device must be adapted on the sewing machine as illustrated in FIGURE 1. The spring 30 is positioned around bar 14 between the end portion 22 of sleeve 20 and the collar 25. Thus, a downward reciprocation of the drive bar 14 will compress the spring 30 to cause an upward biasing force between the sleeve 20 and the collar 25. A proper adjustment of collar 25 by means of set screw 27 will insure a sufficient compression of spring 30 to bias the drive bar 14 to an upper stroke limit, as shown, whenever the transmitter foot pedal is at a neutral position. Since the needle bar mechanism is free from engagement with either the clutch or brake, the bias of spring 30 will cause the needle 15 to stop at the upper stroke limit. It is understood, that the tension of spring 30 be sufficient to motivate the needle bar mechanism when free, however, insufficient to interfere with the operation of the machine whenever the clutch or brake are adequately engaged.

FIGURE 3 shows the invention adapted to position the needle at the downward stroke limit. This may be quickly and easily accomplished from the adaption shown in FIGURE 1 by unscrewing cap 35 and set screw 27 to remove collar 25 and spring 30. The collar and spring are quickly replaced in reverse positions, with the spring 30 around the bar 14 and above the collar 25, as indicated in FIGURE 3. The collar 25 is positioned at a point on bar 14 above end portion 22 of sleeve 20 whenever the bar 14 is at the downward stroke limit. The collar 25 is affixed in position on the bar 14 by tightening set screw 27. The cap 35 is replaced on the threaded end portion 22 to enclose the upper end of bar 14, collar 25 and the spring 30 with one end of the spring 30 bearing against surface 37 of the cap 35. An upward reciprocation of the drive bar 14 will compress the spring 30 and cause a downward biasing force between the collar 25 and the surface 37 of cap 35. Thus, whenever the transmitter foot pedal is at a neutral position, the compression of spring 30 will bias the drive bar 14 to a downward stroke limit.

A partial reverse rotation of the drive bar mechanism may occur during operation of either of the adaptions, described above, of the invented device. Some of the

standard rotary shuttle hooks are designed for rotation in a single direction and do not provide for a reverse rotation. That is, certain projections and notches on the rotary shuttle hook would snag and break the bobbin thread upon a reverse rotation. FIGURE 4 illustrates a standard rotary shuttle hook 18 which has been modified to provide for a reverse rotation. During the sewing operation, the rotary hook 18 rotates in the direction indicated by the arrow, around the bobbin 51. The bobbin 51 is secured in hook 18 by a detachment arm 54, which includes a fingernail tab 55 for convenience in removing the bobbin. The tab 55 allows the passage of thread in the direction of the arrow, however, also provides an interfering projection for any passage in a reverse direction. Therefore the tab 55 must be removed or bent inward as illustrated to provide a cambered surface permitting passage of thread in a reverse direction. Additionally, the standard hook 18 may also have a notch (shown in phantom) for passage of the needle, which notch serves as a hook to snag thread upon reverse rotation. The notch may be filled by soldering or brazing to form a cambered edge 56 which will allow a reverse rotation without snagging of thread. Naturally, if necessary, the timing of the needle may be delayed slightly by an adjustment well known in the art. Furthermore, the shuttle hook 18 may be manufactured as described above to eliminate need for any modification.

The present invention may be embodied in other specific forms without departing from the spirit or essential attributes thereof, and accordingly, reference should be made to the appended claims, rather than to the foregoing specification as indicating the scope of the invention.

What is claimed is:

1. On a sewing machine head having an aperture through the top with a needle drive bar reciprocating therethrough between upper and lower stroke limits, an automatic positioner for said bar, comprising: a sleeve affixed in said aperture between said head and said bar, said sleeve including an externally threaded portion extending above said top; a collar removably affixed on said bar over said sleeve; a biasing means bearing against said collar and urging said bar in a direction parallel to reciprocation thereof, to position said bar, while said sewing machine is at rest, at a stroke limit of said reciprocating drive bar upon cessation of said reciprocation; and a hollow elongated tubular cap with an open internally threaded end engaging said threaded portion to enclose the upper end of said bar, collar and biasing means, said cap being readily unscrewed and said collar readily removed for an interchange of said biasing means to alternate positions between said collar and sleeve and said collar and cap, respectively, thereby providing a selective positioning of said bar to one of said stroke limits.

2. An automatic positioner according to claim 1 wherein said biasing means is a helical coil compression spring around said bar.

3. An automatic positioner in accordance with claim 2 in combination with a rotating shuttle hook having cambered edges and surfaces allowing a reverse rotation thereof without snagging and breaking of thread thereon.

4. On a sewing machine head having an aperture through the top with a needle drive bar reciprocating between upper and lower stroke limits, an automatic needle bar positioner, comprising: an elongated replacement bar in place of said drive bar to provide a drive bar extension above said top; a sleeve affixed in said aperture between said head and said replacement bar, said sleeve including an externally threaded portion extending above said top; a removable collar on said drive bar extension; a set screw extending radially inward through said collar to provide a selective removal and positioning of said collar on said bar extension; a helical coil compression spring around said bar extension, said spring having an end against said collar to urge said replacement bar in a direction parallel to reciprocation thereof and position said replacement bar, while said sewing machine is at rest,

at a stroke limit of said reciprocating replacement bar upon cessation of said reciprocation; and a hollow elongated tubular cap with an open internally threaded end engaging said threaded portion of said sleeve to enclose the upper end of said bar extension, collar and spring, said cap being readily removable for an interchange of said spring to alternate positions between said collar and sleeve and said collar and cap, respectively, thereby providing a selective positioning of said replacement bar to one of said stroke limits.

5. An automatic positioner in accordance with claim 4 in combination with a rotating shuttle hook having cambered edges and surfaces allowing a reverse rotation thereof without snagging and breaking of thread thereon.
